UNITED STATES PATENT OFFICE.

GEORGE WILKINSON, OF PROVIDENCE, RHODE ISLAND, ASSIGNOR TO
GORHAM MANUFACTURING COMPANY, OF SAME PLACE.

DESIGN FOR SPOON AND FORK HANDLES.

Specification forming part of Design No. 9,603, dated October 24, 1876; application filed August 26, 1876.
[Term of Patent 7 years.]

To all whom it may concern:

Be it known that I, GEORGE WILKINSON, of the city and county of Providence, and State of Rhode Island, have invented a new and original Design for the Handles of Spoons and Forks in Silver and Plated Wares, of which the following is a specification:

In the accompanying photograph, Figure 1 represents a front view of the design, which consists of a raised border-line, *a*, enclosing the main features of the design, as shown in the said photograph. At about the center portion of the design the border-line encircles two (2) rosettes, *b b*, from the centers of which droop small ornamental figures *c c*, and above the said rosettes rises an orna-

ment consisting of nine, more or less, curved raised lines, *d*, and underneath the rosettes is an ornamental pendant, *f*, all of which features of said design are substantially as shown in the photograph. Fig. 2 represents the reverse view of the said design.

I claim as my invention—

The design for spoon and fork handles, substantially as herein set forth, and shown in the accompanying photograph.

GEORGE WILKINSON.
